(57) **CLAIM**

(21) Appl. No.: **29/949,498**

The ornamental design for a baby feeding chair with building block table, as shown and described.

(22) Filed: **Jun. 27, 2024**

DESCRIPTION

(51) LOC (14) Cl. **06-01**

FIG. 1 is a perspective view of a baby feeding chair with building block table showing my new design;
FIG. 2 is another perspective view thereof;
FIG. 3 is another perspective view thereof;
FIG. 4 is a front elevational view thereof;
FIG. 5 is a rear elevational view thereof;
FIG. 6 is a left side elevational view thereof;
FIG. 7 is a right side elevational view thereof;
FIG. 8 is a top plan view thereof;
FIG. 9 is a bottom plan view thereof;
FIG. 10 is an exploded perspective view of the baby feeding chair with building block table;
FIG. 11 is an enlarged view of portion 11 shown in FIG. 3;
and,
FIG. 12 is an enlarged view of portion 12 shown in FIG. 3.
The dash-dash broken lines in the drawings depict portions of the baby feeding chair with building block table that form no part of the claimed design. The dot-dash broken lines in FIGS. 3 and 11-12 represent boundaries of the enlarged portions and form no part of the claimed design.
